(57) **CLAIM**

We claim the ornamental design for a capacitive touch sensor with a light emitting diode, as shown and described.

DESCRIPTION

FIG. 1 is a perspective view of a capacitive touch sensor with a light emitting diode showing our new design;

FIG. 2 is a top view of the capacitive touch sensor with the light emitting diode;

FIG. 3 is a bottom view of the capacitive touch sensor with the light emitting diode;

FIG. 4 is a side view of the capacitive touch sensor with the light emitting diode;

FIG. 5 is a front view of the capacitive touch sensor with the light emitting diode; and,

FIG. 6 is a rear view of the capacitive touch sensor with the light emitting diode.

The broken lines in the FIGURES showing the connector and cable are for illustrative purposes only and form no part of the claimed design.
